BUILDING STRUCTURE

Ole Elias Carlson, San Francisco, Calif.

Application September 18, 1936, Serial No. 101,508

3 Claims. (Cl. 72—39)

This invention relates to a new improvement in building structures and particularly to an improved wall construction and improved roof construction and an improved ceiling construction, all arranged to agree in general formation so that one part will readily cooperate and interfit into the other part to make a complete construction.

Further the invention consists in the provision of novel means in enabling the use of precast wall, roof and floor building units of reinforced concrete to the end that the use of much of the elaborate and expensive temporary form work heretofore commonly used in building concrete structures is dispensed with.

The invention, together with its objects and advantages will be best understood from a study of the following description taken in connection with the accompanying drawings, wherein:

Figure 1 is an enlarged sectional view through a portion of a building constructed in accordance with the present invention.

Figs. 2 and 3 are edge elevational views taken substantially on the lines 2—2 and 3—3 respectively, of Fig. 1.

Fig. 4 is a detail vertical sectional view showing a modified form of roof structure.

Fig. 5 is an enlarged fragmentary detail sectional view showing the manner of joining two adjacent concrete slabs together.

Fig. 6 is a fragmentary horizontal sectional view through a building structure at an outer corner of the latter.

Fig. 7 is a view similar to Fig. 6 and illustrating an inner corner construction.

Referring to the drawings by reference numerals, and in accordance with the present invention, I provide a number of pre-cast reinforced concrete unit plates or slabs 5 and 6 respectively. The slabs 5 are preferably of a length corresponding to the full height of the building, while the slabs 6 are of a length corresponding to the width or depth of the structure as may be found desirable.

Each of the slabs 5 has one longitudinal edge which is provided with an integral reinforced concrete rib or flange 7 as is also each slab 6, the reinforced rib or flange of each slab 6 being indicated by the reference numeral 8.

At the junction of a plate 5 and its rib 7 and extending for the full length of the plate, said plate is provided with a rabbeted or grooved edge 9 while the opposite longitudinal edge of the plate 5 is beveled as at 10 to conformably fit

into the groove 9 of the next adjacent plate 5 as clearly shown in Fig. 2.

Each of the plates 6 is laterally extended beyond its rib or flange 8 and at the edge thereof is rabbeted or otherwise provided to provide a groove 11 with which is engaged the squared longitudinal free edge of the next adjacent plate or slab 6 as shown in Fig. 3.

As shown in Figs. 1, 2, 5, 6 and 7, the slabs 5 are preferably resorted to for forming the vertical walls or partitions of the building with the rib 7 thereof disposed perpendicularly. With the slabs positioned and interlocked as shown, they provide a smooth outside wall surface to which is applied a finishing coat 12 of cement plaster or the like.

Embedded in, or otherwise made permanent with, or integral with the free edges of the rib 7 of the slabs 5 and extending for the full length of the rib 7 are wood strips 13 to which are nailed the plaster lathes 14 for use in providing plaster inner wall surfaces for the building.

Where desired, and as suggested in Fig. 5, there may be provided at the joint between adjacent slabs or plate units 5 poured or run-in-place molding strips 15 in which are embedded at intervals, tie wires 16 engaged with loops reinforcing wires 17 provided in the slab units 5 and ribs 7, as clearly shown in Fig. 5. Thus through the medium of the loop wires 17, the tie wires 16, and the molding strips 15 a positive and efficient joint is provided between adjacent plate units 5.

In Fig. 6 is detailed a section of an outer corner of a building constructed of the slabs 5. As shown, at each corner there is provided a pre-cast reinforced concrete corner strip 18 having two right angularly disposed sides, the strip 18 being segmental in cross section and having integral with its convex side, an inwardly extending rib or flange 19, there being provided at the junction of the strip 18 and the rib 19 at opposite sides of the rib, grooves 20 to accommodate the beveled edges of the adjacent slabs 5. At its free edge, the rib 19 is provided with a V-shaped groove into which is fitted and united with the rib 19, a wood strip 21 grooved as at 22 to receive the ends of the lathes 14 in a manner clearly shown in Fig. 6.

Fig. 7 is a section through an inner corner, or in other words, through the corner joint between two right angularly related interior walls or partitions which latter are formed of slabs 5 as shown. In this form of corner construction, the end-most slab 5 of one wall intermediate its

longitudinal edges is provided with a groove 23 to receive the beveled free longitudinal edge of the end slab 5 of the right angularly related wall.

Preferably the slabs 6 are used for forming the floors 24 and roof 25.

5 In forming either the floor 24 or the roof 25, or both, the slabs 6 are arranged with the free longitudinal edge of each slab engaging in a groove 11 in the next adjacent slab while to the lower free longitudinal edges of the ribs 8 there 10 are secured in any suitable manner and positively united with the ribs, wood strips 26 to which are nailed the lathes 27 used in constructing the plaster ceiling.

15 Also in forming the floor 24, strips 28 are provided with ribs 29 received in the grooves 11, and to the strips 28 are secured in the usual manner, the wood flooring 30. See Fig. 3.

For supporting the floors 24, and the roof 25, 20 if desired, resort may be had to poured or run-in-place reinforced piers or pillows 31.

Also at the joints between the wall slabs 5 and the ceiling and floor slabs 6 poured or run-in-place reinforced concrete beams 32 are resorted to. In Fig. 1 is also illustrated the application of the invention in a building involving a gable roof construction, the rafters for the roof indicated by the reference numeral 33. Where such a roof construction is employed, cleats 34 of wood or similar material are anchored to the uppermost joists 32 through the medium of anchoring bolts 35.

In Fig. 4 is illustrated the application of the invention where a tar and gravel roof is resorted to in a flat roof construction. In such a construction the top surfaces of the joists 32 and the roof slabs 6 are coated with tar 36 and over this coating of tar 36 is laid one or more layers of roofing paper.

40 Also in Fig. 4, the invention is illustrated as employed where a suspended ceiling 37 is resorted to.

It is thought that the invention together with

its objects and advantages will be best understood from a study of the following description taken in connection with the accompanying drawings, and without requiring a more detailed description thereof.

Having thus described the invention, what is claimed as new is:—

1. In a building structure, a wall comprising a plurality of vertically disposed concrete slabs, each comprising an outer panel and an inwardly 10 extending right angled flange adjacent one edge thereof, said slabs being rabbeted along the corner of the flanged edge thereof, respectively, and the panel of one slab fitting at its free edge into the rabbet of the adjacent slab and forming together with the flange of said adjacent slab right angled inner faces for said wall, a concrete strip extending along the angle formed by said faces and integral therewith, and reinforcing wires extending through said strip laterally and 15 imbedded in said slabs.

2. In a building structure, a corner wall comprising right angularly related concrete slabs, and a vertically disposed corner slab extending inwardly from said corner and having an outer 20 edge of right angled form in cross-section and opposed grooves upon opposite sides of said edge of acute angled form in cross-section, said slabs each having an edge corresponding in form to said grooves and fitting thereto.

3. In a building structure, a floor comprising a plurality of concrete slabs each including a top panel having along one side edge an under reinforcing rib provided with downwardly convergent side walls, and a flange extending downwardly 35 from said rib at a right angle to said panel, each slab being rabbeted along its ribbed edge and the free edge of one panel overlapping the rabbeted edge of the adjacent panel, and sealing strips of T-shape in cross-section fitting between the overlying edges of said panels and said rabbet and overlapping said panels at the juncture thereof.

OLE ELIAS CARLSON.
